UNITED STATES PATENT OFFICE.

CAROLINE LASSÉN, OF NEW YORK, N. Y.

COLLAR-FASTENING CLASP.

SPECIFICATION forming part of Letters Patent No. 740,289, dated September 29, 1903.

Application filed June 11, 1903. Serial No. 160,984. (No model.)

To all whom it may concern:

Be it known that I, CAROLINE LASSÉN, a citizen of the United States, and a resident of the city of New York, borough of Brooklyn, in the county of Kings and State of New York, have invented new and useful Improvements in Collar-Fastening Clasps, of which the following is a full, clear, and exact description.

The present invention relates to certain novel and useful clasps designed particularly for use in fastening collars used in connection with ladies' shirt-waists.

As is well known, considerable difficulty has always been experienced in providing a secure and suitable means for fastening the light lace collars commonly used by ladies in connection with shirt-waists, and it has been the common practice to fasten the adjoining or overlapping edges of the collar at the rear of the neck through the medium of pins and the like; but many disadvantages are incident to this practice, for beside the danger and possibility of injury by the pins penetrating the flesh such fastenings have proven very insecure, as the pins are liable to work loose in the fabric of the collar and drop out, thereby causing the ends of the collar to separate and loosen and to present a very untidy appearance, besides causing discomfort to the wearer. Primarily, therefore, I have as an object the provision of an improved collar-fastener which shall overcome the objections above recited, such fastener dispensing with pins and enabling such fastenings as hooks and eyes, buttons, and the like to be discarded.

A further object of my invention is to provide a fastening-clasp through the medium of which the collar may be connected to shirt-waists, the structure of the clasp being such that it may readily be removed from one collar and placed upon another and may be adjusted so as to cause a collar of any size to fit snugly and neatly about the neck. I have also in contemplation the provision of an article such as has been referred to which will always retain the collar in a smooth unrumpled condition and which may be ornamented in a suitable manner to present an attractive appearance.

With the above-recited objects and others

of a similar nature in view my invention consists in the peculiar construction, combination, and arrangement of parts, as is described in this specification, delineated in the accompanying drawings, and set forth in the appended claims.

Reference is to be had to the accompanying drawings, forming a part of this specification, in which similar characters of reference indicate corresponding parts in all the figures.

Figure 1 is a perspective view of my improved fastening-clasp and showing the position it occupies on the collar when in position. Fig. 2 is a longitudinal vertical sectional view of a fastening embodying my improvements. Fig. 3 is a cross-sectional view of the same, and Fig. 4 is a perspective view of the clasp detached from the collar.

Referring now to the accompanying drawings in detail, A designates a collar designed to have its end portions *a* and *b* connected through the medium of my improved collar-fastening, which I will now proceed to describe in detail. This fastening comprises, essentially, two members—a base or back member 5 and a top or front member 6—said members being connected at adjacent end portions through the medium of any suitable hinge 7. The base member, which is substantially an elongated plate formed of any suitable material, such as thin metal or the like, is formed with a central open or slotted portion 8, over which open portion extends the relatively long narrow strip or plate 9, said plate being preferably stamped out of the same metal as the member 5 and is curved or projected near its extremities 10 10, so that the strip 9 will lie in the same parallel plane with but slightly above the base member 5, whereby a portion of the collar may be slipped in between the strip 9 and the plate 5 and securely retained thereby. For assisting in maintaining the ends of the collar securely in position in the clasp I provide this central strip 9 with a number of short sharp studs or pins 11 11, said pins being designed to penetrate the fabric of the collar when the ends are brought into position for fastening. The end portion of the back member 5 is tapered or reduced, as at 12, and formed with a grooved portion 13, adapted to seat the clasp-

ing-hook 14 of the top plate 6 when the latter is closed upon the back plate, as when securing the collar.

At the lower portion of the back plate and upon the opposite side from that carrying the pins 11 11 is secured a small projecting button 15, designed to enter a buttonhole in the neckband of the shirt-waist, so that the collar may be securely connected with and held snugly in position relative to the shirt-waist neckband. This button may be of any desired or preferred character and may be connected directly to the back plate or may be mounted upon a transverse strip 16, Fig. 4, connected to the aforesaid back member.

From the above description, taken in connection with the accompanying drawings, the construction and manner of employing my improved fastening will be readily apparent.

The clasp is slipped upon one end of the collar by passing said collar end in between the strip 9 and the back plate, and the opposite end of the collar is then secured within the fastening in such manner that the small studs or pins 11 11 penetrate the material and hold the ends of the collar in a connected or closed position. The hinged top plate of the clasp is then brought down, and the catch or hook 14 makes locking engagement with the tongue portion 12 of the back plate. A collar thus fastened is not liable to become easily disengaged or unhooked and will always present a neat and tidy appearance. The top plate 6 may be ornamented in any suitable and desired manner and may be formed of any material suitable for the purpose. The shape of the plate may also be varied and other changes in minor details and in proportions to the parts may be made without affecting the invention, for while I have shown and herein described one embodiment of my fastening I wish it to be understood that I do not confine myself to the precise features of construction recited and shown, as there may be modifications and variations with respect to details without departing from the spirit or scope of the invention or sacrificing any of the advantages thereof.

Having thus described my invention, I claim as new and desire to secure by Letters Patent—

1. A fastening device comprising hinged plates, a strip stamped from one of said plates and spaced apart therefrom the greater portion of its length, the construction being such that a collar or similar article may be passed between the strip and the plate, and means carried by said strip for engaging and penetrating the collar, substantially as set forth. 55

2. A fastening device, comprising plates hinged at one end, a hook formed at the free end of one of said plates, a tongue on the free end of the opposite plate designed to be engaged by said hook for locking the plates in a folded position, a button carried by one of said plates, and a strip formed integral with one of the plates but extending spaced apart the greater distance thereof, the construction being such that a collar or similar article may be passed between the plate and the strip. 60 70

3. A fastening device comprising a base-plate, a strip formed centrally longitudinally of the base-plate but spaced apart therefrom the greater part of its length, the construction being such that a collar or similar article 75 may be passed between the plate and the strip, pins carried by said strip for engaging the collar, a top plate hinged to the base-plate, and means for locking the plates together in a folded position. 80

4. The combination of a top plate and a base-plate, a hinge connecting said plates, a strip formed integral with the base-plate but spaced apart therefrom the greater portion of its length, the construction being such that the end of a collar or like article may be fastened between the strip and the base-plate, projections mounted on the strip for engaging with the collar, a button carried by the back plate at the lower end thereof, and a hook formed on one of said plates for engaging with a tongue on the opposite plate whereby said plates may be locked together, substantially as set forth. 85 90

In testimony whereof I have signed my name to this specification in the presence of two subscribing witnesses.

CAROLINE LASSÉN.
